United States Patent Office

Des. 182,967
Patented June 3, 1958

182,967

SLIDE FILE BOX OR SIMILAR ARTICLE

Herbert R. Leopold, Havertown, Pa., and Clarence B. Mitchell, Chicago, Ill., assignors to Optics Manufacturing Corporation, Philadelphia, Pa., a corporation of Illinois

Application July 24, 1957, Serial No. 47,071

Term of patent 14 years

(Cl. D61—1)

FIG. 1

FIG. 2

FIG. 3

FIG. 4

Fig. 1 is a front perspective view of a slide file box or similar article, showing our new design;

Fig. 2 is a rear elevational view;

Fig. 3 is a side elevational view, the opposite side being a substantial mirror image thereof;

Fig. 4 is a bottom plan view; and

Fig. 5 is a perspective view thereof in open position.

We claim:

The ornamental design for a slide file box or similar article, as shown and described.
